(57) **CLAIM**

The ornamental design for a lid for beverage container with straw holder, as shown and described.

DESCRIPTION

FIG. 1 is a top perspective view of a lid for beverage container with straw holder, showing our new design; FIG. 2 is a right side view of the lid for beverage container with straw holder illustrated in FIG. 1;

FIG. 3 is a left side view of the lid for beverage container with straw holder illustrated in FIG. 1;

FIG. 4 is a rear view of the lid for beverage container with straw holder illustrated in FIG. 1;

FIG. 5 is front view of the lid for beverage container with straw holder illustrated in FIG. 1;

FIG. 6 is a top view of the lid for beverage container with straw holder illustrated in FIG. 1; and,

FIG. 7 is a bottom view of the lid for beverage container with straw holder illustrated in FIG. 1.

The broken lines shown in the drawings are included for the purpose of illustrating environmental structure and form no part of the claimed design.

1 Claim, 6 Drawing Sheets
